MAGNETIC ASSEMBLY FOR ELECTRIC
TIMEPIECE

Fred Koehler and Donald A. Bly, Lancaster, Pa., assignors to Hamilton Watch Company, Lancaster, Pa., a corporation of Pennsylvania

Filed June 20, 1958, Ser. No. 743,370
8 Claims. (Cl. 317—158)

This invention relates to an electric clock and more particularly to that part of the clock which furnishes the motive power for operating the oscillating balance wheel.

The electromagnetic assemblies of certain types of electric clocks contain U-shaped cores with in-turned core legs and with coils mounted on the legs. In the assembly of this unit it is a customary practice to wind the coils upon a core after the core is fully assembled, the in-turned ends of the core extending beyond the ends of the coils to form the pole pieces which are used to attract an armature or the like. This construction makes the winding of the coils on the core a difficult operation and with certain shapes of cores it is almost impossible to wind the coils without the cost being prohibitive.

It is accordingly a primary object of this invention to provide a laminated or multi-piece core which may be assembled after the coil has been wound and which will provide practically the same magnetic transference as a solid core.

It is a further object of the present invention to provide a multi-piece core substantially U-shaped with the legs diverging to lessen the leakage across the legs and to concentrate the flow of flux through pole pieces which are attached to the core and extend substantially at right angles to the legs of the U-shaped core.

It is another object of the invention to utilize the ends of a laminated core of the coil to substantially cover the ends of the armature so that the magnetic field is intensified and substantially restricted.

It is another object of the present invention to make the core of six individual pieces which are fabricated in three pairs to provide interchangeability and economy in manufacturing.

It is a still further object of the present invention to provide a small tolerance between the individual parts making up the core so that during the mounting operation of the coil in the watch the pieces may be slightly spaced to provide for any inaccuracies in the hole placement.

These and further objects and advantages of the invention will become more apparent on reference to the following specification and claims and appended drawings in which:

FIGURE 1 is a top plan view of a core and coil assembly according to the invention with the coils shown in cross section;

FIGURE 2 is an end view of the assembly of FIGURE 1;

FIGURE 3 is a side elevation of the assembly of FIGURE 1 with the coil shown in cross section;

FIGURE 4 is a plan view of one of the core pieces;

FIGURE 5 is a plan view of another of the core pieces; and

FIGURE 6 is a plan view of the third core piece.

Referring particularly to FIGURES 4, 5 and 6, the parts which make up the laminated core are made in three identical pairs. One of these core pairs is illustrated in FIGURE 4, the second is illustrated in FIGURE 5, and the third is illustrated in FIGURE 6.

The substantially U-shaped part illustrated in FIGURE 4 is formed with a base portion 12, a short leg 14 and a long leg 16, the legs and base being of one piece of flat sheet material which is preferably stamped. The

base 12 is formed with a central hole 18 used in positioning the completed coil in the time piece.

The part illustrated in FIGURE 5 is substantially V-shaped with a rounded apex portion 20, a long leg 24, and a pole piece 26. This is referred to as the large V-member. The apex portion 20 of the V-member is apertured at 22 and this aperture is used to position the completed assembly in the watch or clock.

The part shown in FIGURE 6 is very similar to the one shown in FIGURE 5 and is referred to as the small V-member. This member has a rounded apex portion 28 formed with a central hole 30, a pole piece 32 and a short leg 34.

Referring particularly to FIGURE 1, when the core 15 is assembled the base portions of the two U-shaped members 12 are superimposed so that the upper long leg 16 of one piece is superimposed over the upper short leg 14 of the other piece, and conversely, the lower short leg of the first piece is above the lower longer leg of the 20 second piece. The V-members shown in FIGURES 5 and 6 are mounted in this assembly with their respective legs 24 and 34 abutting the ends of the legs of the U-shaped members. Thus referring to FIGURE 1, the upper leg of the assembly in the drawing has a long leg 24 25 of the large V-member shown in FIGURE 5 abutting the short leg 14 of the bottom U-shaped member, and has a short leg 34 of the small V-member shown in FIGURE 6 abutting the long leg 16 of the U-shaped member. The lower leg of the assembly is conversely assembled.

In order that the tolerances between the holes 18, 30 35 and 22 need not be so rigid as to require unduly accurate dimensioning, it is desirable to provide slight air gaps at the abutments 36 and 38 of the legs of the U-shaped members and the legs of the V-members shown in FIGURES 5 and 6. The overlapping of the legs of the U-shaped members and the legs of the V-members provides good magnetic transference throughout the laminated core and also tends to minimize stray fields 40 which might be formed where there was an air gap.

The coils 40 are identical and are prewound and then separately slipped onto the legs of the U-shaped members. The legs of the V-members are then inserted into position. 45 This particular method of laminating the core structure makes for ease of assembling and ease in manufacturing.

Referring particularly to FIGURE 2, it will be seen that the pole pieces 26 and 32 of the U-members are 50 identical and are bent at 42 and 44 respectively to provide a gap 46 through which an armature may pass. The gap 46 tends to intensify and restrict the magnetic field thus supplying a maximum of magnetic flux at the point at which it is required while preventing or minimizing the 55 effect of a large magnetic field on the other parts of the timepiece such as the hairspring, the gear train wheels and the pivot staffs.

The invention may be embodied in other specific forms without departing from the spirit or essential characteristics thereof. The present embodiment is therefore 60 to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. An electromagnet for an electric timepiece comprising 65 a pair of identical substantially U-shaped core pieces each having a base and a long and a short leg; said core pieces being arranged in overlapping relationship so that

their bases coincide and the long leg of each piece overlies the short leg of the other piece; two pairs of laminated pole pieces, each pair comprising two laminae each having angularly arranged first and second portions; the first portion of the first lamina being longer than the first portion of the second lamina; each pair of pole pieces being associated with one pair of overlapping legs of said core pieces so that the first portion of the first lamina of said pair of pole pieces overlaps the long leg of said core pieces; the end of said long leg being adjacent the end of the first portion of the second lamina of said pair of pole pieces; and a pair of coils each disposed about the overlapping legs and first portions of said associated core pieces and pole pieces.

2. An electromagnet as defined in claim 1 wherein said pole pieces are generally U-shaped; the second portions of said pole pieces being formed at substantially right angles to their respective first portions.

3. An electromagnet as defined in claim 1 wherein the second portions of the laminae in each pair of pole pieces are spaced from one another to form a bifurcation; the open ends of the two bifurcations facing one another and the two pairs of pole pieces being arranged so as to permit an armature to rotate with its ends passing within the two bifurcations.

4. An electromagnet as defined in claim 1 wherein said long and short legs of said U-shaped core pieces diverge from the bases of said pieces.

5. An electromagnet for an electric timepiece comprising a pair of coils; a pair of identical substantially U-shaped core pieces each having a base and a long and a short leg; the base and the legs of each piece being arranged in overlapping relationship with the respective base and legs of the other piece so that the short leg of one piece overlies the long leg of the other piece; and a laminated pole piece associated with each mating pair of legs; each pole piece having a first portion formed of two laminae of different lengths to conform to its associated pair of mating long and short legs of said core pieces; the long legs of said associated core and pole pieces overlapping one another; each pole piece having a second portion formed at an angle to the first portion of

said piece and extending in the direction of the second portion of the other pole piece; said coils being disposed about the overlapping legs of said core and pole pieces.

6. An electromagnet for an electric timepiece comprising a pair of substantially U-shaped core pieces each having a base and two legs; the base and legs of one of said pieces overlying the respective base and legs of the other of said pieces; the legs of each core piece being constructed relative to one another and to the legs of the other core piece so that one of the legs on each side of the U is longer than the other leg on the same side of said U; two pairs of laminated pole pieces, each pair comprising two laminae each having angularly arranged first and second portions; the first portion of the first lamina being longer than the first portion of the second lamina; each pair of pole pieces being associated with one pair of overlapping legs of said core pieces so that the first portion of the first lamina of said pair of pole pieces overlaps the long leg of said associated pair of legs; the end of said long leg being adjacent the end of first portion of the second lamina of said associated pair of pole pieces; the second portions of the laminae in each pair of pole pieces being spaced from one another to form a bifurcation; the open ends of the two bifurcations facing one another and the two pairs of pole pieces being arranged so as to permit an armature to rotate with its ends passing within the two bifurcations; and a pair of coils each disposed about the mated legs and first portions of said associated core pieces and pole pieces.

7. An electromagnet according to claim 5 wherein the ends of said second portions of said pole pieces are bifurcated to permit an armature to reciprocate between the furcations of each such portion.

8. An electromagnet according to claim 5 wherein said long and short legs of said U-shaped core pieces diverge from said base.
